UNITED STATES PATENT OFFICE.

JOSEPH DERK, OF DOYLESTOWN, PENNSYLVANIA, ASSIGNOR TO THE DERK MANUFACTURING COMPANY, OF DOYLESTOWN, PENNSYLVANIA, A CORPORATION OF PENNSYLVANIA.

DESIGN FOR A TEXTILE FABRIC.

Application filed January 19, 1928. Serial No. 24,936. Term of patent 3½ years.

To all whom it may concern:

Be it known that I, JOSEPH DERK, a citizen of the United States, residing at Doylestown, in the county of Bucks, State of Pennsylvania, have invented the new, original, and ornamental Design for a Textile Fabric, of which the following is a specification, reference being had to the accompanying drawing, forming part thereof.

The figure is a plan view of a textile fabric, showing my new design.

I claim:—

The ornamental design for a textile fabric, as shown.

JOSEPH DERK.
